ATTORNEY

UNITED STATES PATENT OFFICE.

MORRIS A. KAMINETSKY, OF PASSAIC, NEW JERSEY.

SMOKE-BELL SUPPORT.

1,211,317.

Specification of Letters Patent. Patented Jan. 2, 1917.

Application filed October 14, 1915. Serial No. 55,884.

To all whom it may concern:

Be it known that I, MORRIS A. KAMINETSKY, a citizen of the United States, residing at Passaic, in the county of Passaic and State of New Jersey, have invented certain new and useful Improvements in Smoke-Bell Supports, of which the following is a specification.

My invention relates to supports, and more particularly to a heat deflector support for use in connection with illuminating gas fixtures.

The primary object of my invention is to provide a device of the character above mentioned adapted for detachable securement to a gas fixture whereby to support and retain a carrying bracket having a deflector associated therewith.

Another object of my invention is to provide a device of the character above mentioned so constructed that a plurality of deflectors may be supported on a chandelier or the like.

A further object of my invention is to provide a clamping support which allows the use of the device whereby to carry a deflector on the ordinary straight wall fixture.

A still further object of my invention is to provide a supporting device of the character above mentioned in which the parts may be quickly and easily disassembled for packing and shipping, the structure being light, cheap to manufacture, and strong and durable.

With the above and other objects in view my invention resides preferably in the construction, combination and arrangement of parts as hereinafter set forth in the specification and illustrated in the accompanying drawings in which,

Figure 1 is a plan view of one form of my invention. Fig. 2 is a side elevation of the same. Fig. 3 is a side elevation of a modified form of my invention. Fig. 4 is an end elevation of the same, partly broken away.

Similar reference characters indicate similar parts throughout the various views of the drawings.

In the drawings, wherein the preferred embodiment of my invention is illustrated, in the first form thereof I provide a supporting member formed of a single strip of bendable metal, slightly resilient, having a loop 1 and divergent arms 2 and 3. Said arms normally tend to remain remote from one another and a clamping screw 4 having

a wing nut 5 is disposed through said arms for clamping. The free extremities of the arms 2 and 3 are provided with curved clamping jaws 6 and 7, respectively, adapted to embrace the vertical suspending post or rod of the usual type of chandelier. In this form of my invention a plurality of deflector carriers are adapted to be supported thereby, said jaws 6 and 7 being provided with receiving loops described in detail hereinafter.

The loops hereinbefore mentioned are provided by slotting the jaws 6 and 7, and rolling the metal struck therefrom to form said loops, the loops being designated 8 and 10.

In Fig. 3 I have illustrated a modified form of my invention, this form being adapted for use in connection with gas fixtures which project laterally from a wall and are disposed in a horizontal plane. In this form of my invention I provide a clamping member formed of a strip 12 of metal bent upon itself to provide resilient clamping jaws 13 and 14 preferably resilient in nature, a retaining screw 15 being provided having a wing nut 16 thereon. The strip 12 is offset outwardly to provide longitudinally arranged grooves 17 in the arms, an opening 18 being formed in the strip at the point at which the same is bent upon itself. A supporting rod 18' is receivable in said grooves 17 and is provided with a lateral portion 19 supporting a deflecting plate 20 of any suitable type. When the wing 16 is tightened the rod will be secured in position. The lamp is designated 21 and may be of any usual type.

The uses to which the above described forms of my invention may be placed need not be enumerated here and it will be noted that both a vertical and horizontal adjustment of the device is facilitated in both forms of the invention.

It is to be understood, of course, that, while I have described the invention as adapted for use in supporting heat deflectors, the scope of its uses is practically unlimited. The outer extremity of the jaw 7 is rolled to provide a supporting loop 9.

While I have shown and described my invention as possessing a peculiar form and construction, it is desired that it be understood that I may make such changes in the details thereof that do not depart from the spirit and scope of the invention as claimed.

Having thus described my invention, what

I claim and desire to secure by Letters Patent, is:

1. A supporting bracket comprising a strip of resilient metal bent upon itself to form divergent arms, said arms having the free extremities thereof bent to provide clamping jaws, and a plurality of tongues struck from said clamping jaws and rolled upon themselves to constitute loops, as and for the purpose set forth.
2. A supporting bracket, comprising a strip of resilient metal bent upon itself to form divergent arms, said arms having the extremities thereof bent to provide clamping jaws, clamping means arranged upon said arms, and a plurality of complementally formed tongues struck from each of said clamping jaws and rolled upon themselves to constitute vertically disposed supporting loops.
3. A supporting bracket, comprising a strip of resilient metal bent upon itself to form divergent arms, said arms having the free extremities thereof bent to provide clamping jaws, clamping means arranged

upon said arms, longitudinally disposed reinforcing ribs arranged upon the divergent arms, and a plurality of complementally formed tongues struck from each of the clamping jaws and rolled upon themselves to constitute vertically supporting loops.

4. A supporting bracket, comprising a strip of resilient metal bent upon itself to form divergent arms, a loop formed adjacent the point of bending of such arms, clamping jaws arranged upon the free extremities of the arms, clamping means carried by said arms, and a plurality of complementally formed tongues struck from each of the clamping jaws and rolled upon themselves to constitute vertically disposed supporting loops, as and for the purpose set forth.

In testimony whereof I affix my signature in presence of two witnesses.

MORRIS A. KAMINETSKY.
